UNITED STATES PATENT OFFICE.

NEWTON J. BISHOP, OF WASHINGTON, DISTRICT OF COLUMBIA.

WINDOW-SASH HOLDER.

Application filed March 7, 1922. Serial No. 541,738.

To all whom it may concern:

Be it known that I, NEWTON J. BISHOP, a citizen of the United States, residing at Washington, in the District of Columbia, 5 have invented a new and useful Window-Sash Holder; and I do hereby declare the following to be a full, clear, and exact description of the invention, such as will enable others skilled in the art to which it applies 10 to make and use the same.

The invention relates to window sash holders, and has for its object to provide a device of this character comprising a sash engaging arm for engaging the upper sash, 15 a downwardly and inwardly inclined lower sash engaging arm for limiting the upward movement of the lower sash, and an expansible loop adapted to be received in the groove of the window frame adjacent the 20 parting strip and forming means for supporting the device adjacent the side rail of the upper sash. The expansible loop also forms means whereby the device may be supported in various widths of grooves.

25 A further object is to form the device from a single piece of wire, thereby reducing the cost of manufacture to a minimum and allowing the device to be formed from standard material of different gauges.

30 With the above and other objects in view the invention resides in the combination and arrangement of parts as hereinafter set forth, shown in the drawings described and claimed, it being understood that changes 35 in the precise embodiment of the invention may be made within the scope of what is claimed without departing from the spirit of the invention.

In the drawings:—

40 Figure 1 is a perspective view of a portion of the window frame showing the sash therein, and the window fastener applied thereto.

45 Figure 2 is a front elevation of the fastener.

Figure 3 is a side elevation of the fastener.

50 Figure 4 is a detail perspective view of the outer side of the fastener, showing the parts slightly open for better illustrating the various convolutions.

55 Referring to the drawings, the numeral 1 designates the side of a conventional form of window frame and 2 a vertically disposed groove in said side in which the lower sash 3 moves. One side of the groove 2 is

formed by the parting strip 4 on the outside of which parting strip the upper sash 5 is vertically slidable in the usual manner. It is the custom to lower the upper sash 60 or raise the lower sash, or both for ventilating purposes, however when this is done the entrance of burglars and the like through the window is not prevented, and to overcome this difficulty the sash holder 6 is provided, which locks or prevents the sash from being moved beyond a predetermined distance, therefore allowing the sash to be adjusted sufficiently to allow passage of air for ventilating purposes, and at the same 65 time not sufficient to allow entrance of a burglar.

The window fastener 6 is formed from a single piece of wire, preferably heavy gauge spring wire and comprises an expansible loop 7 adapted to be received in the sash groove 2 and to expand and engage the side walls of the groove in such a manner as to support the fastener 6 adjacent the upper sash 2. By providing the 75 expansible loop 7, the device may be supported in sash grooves 2 of different widths, thereby allowing the fastener to be applied to different types of window frames and to different sizes of window frames. The wire 80 after the loop 7 is formed bends outwardly at 8 thereby providing an outwardly extending horizontally disposed portion 9, which portion is bent to form an eye 10 and then a plurality of convolutions 11. After 85 the convolutions 11 have been formed the wire extends downwardly thereby forming an arm 12, and thence is bent upwardly thereby forming an arm 13, and at the same time forming an inclined U-shaped lower 90 sash engaging member 14. After the arm 13 has been formed the wire is bent to provide a plurality of convolutions 15 of equal size which convolutions add a spring action to the device, and at the same time engage and bind against the upper sash 5 when the lower sash 3 is forced upwardly 95 onto the member 14, and assist in preventing the fastener from slipping. The wire, after being bent to form the convolutions 100 15, extends upwardly through the eye 10 as shown at 16 and terminates in an inwardly extending and upwardly extending arm 17, the right angled portion 18 of which engages the sash 5 and if so desired said 105 arm may be provided with a prong 19 adapted to be imbedded in the sash 5 for

additionally preventing slipping of the fastener when either sash is moved towards the adjacent sash. The eye 10 braces the arms 17 and stiffens the same so that the right angled arm 18 frictionally engages the sash 5.

From the above it will be seen that the fastener is supported from the groove 2 and that the fastener may be so positioned that the upper and lower sash may be positively limited in movement in an open direction for a predetermined distance, thereby allowing the sash to be adjusted for ventilating purposes, and at the same time preventing entrance of unauthorized persons. If so desired the prong 19 may be eliminated and the two sashes held by the frictional engagement of the right angled arm 18 and the sash engaged arm 14.

The invention having been set forth what is claimed as new and useful is:—

1. The combination with a window fastener having sash engaging members and located adjacent a sash groove, of means carried by said fastener and disposed within the groove for supporting said fastener, said means comprising a contractible and expansible member engaging the walls of the groove.
2. The combination with a window fastener having sash engaging members and located adjacent a sash groove, of means carried by said fastener and disposed within the groove for supporting said fastener, said means comprising an expansible looped member formed from spring material.
3. The combination with a window fastener having sash engaging members and

located adjacent the sash groove, of means carried by said fastener whereby the fastener may be supported adjacent different widths of grooves, said means comprising an expansible looped member formed from spring material and engaging opposite walls of the groove.

4. A window fastener comprising an expansible loop adapted to engage in a sash groove and support the fastener, an outwardly extending arm carried by said loop, said arm terminating in an eye, said eye terminating in a convolution, a U-shaped sash engaging member carried by said convolution, the end of the U-shaped member terminating in a plurality of vertically disposed convolutions, the outer vertically disposed convolution terminating in an upwardly extending sash engaging arm passing through the eye in the outwardly extending arm, said upwardly extending sash engaging arm being provided with a right angled arm and a prong carried by the right angled arm.

5. A window fastener formed from a single piece of wire, said fastener comprising a body portion formed from a plurality of convolutions, a downwardly extending sash engaging member, an upwardly extending sash engaging member and an expansible loop support adapted to be received in the sash groove.

In testimony whereof I have signed my name to this specification in the presence of a subscribing witness.

NEWTON J. BISHOP.

Witness:

W. M. HOFFMAN.
